UNITED STATES PATENT OFFICE.

ALVAH C. ROEBUCK, OF WOODSTOCK, ILLINOIS, ASSIGNOR TO WOODSTOCK TYPEWRITER COMPANY, OF WOODSTOCK, ILLINOIS, A CORPORATION OF ILLINOIS.

PAPER-FEED MECHANISM.

1,207,629.

Specification of Letters Patent.

Patented Dec. 5, 1916.

Application filed October 26, 1914. Serial No. 868,561.

To all whom it may concern:

Be it known that I, ALVAH C. ROEBUCK, a citizen of the United States, residing at Woodstock, in the county of McHenry and 5 State of Illinois, have invented certain new and useful Improvements in Paper-Feed Mechanism, of which the following is a specification.

This invention relates to that part of a 10 typewriting machine which maintains a paper or other material in engagement with the platen, and the principal object of the invention is to provide new and improved mechanism of this class for holding, feeding 15 and adjusting the paper with respect to the platen.

For the attainment of these ends and the accomplishment of other new and useful objects, as will appear, the invention consists in the features of novelty in the construction, combination and arrangement of the several parts generally shown in the accompanying drawings and described in the specification, but more particularly pointed 25 out in the appended claims.

In the drawings, Figure 1 is a front elevation of that part of a typewriter carriage to which the present invention is applied; Fig. 2 is a bottom view of the same; Fig. 3 is a sectional view on the line 3-3 of Fig. 1; Fig. 4 is a view of the operating lever at one end of the carriage; Fig. 5 is a sectional view on the line 5-5 of Fig. 1; Fig. 6 is a view, partly in section, showing 35 the operating lever in one position; Fig. 7 is a similar view showing the operating lever in its other position, and Fig. 8 is a view looking at one end of the paper apron.

In the present construction the feed roller 40 shafts are supported at a distance from their ends, thus lessening their tendency to spring so that all the rollers will bear more evenly on the platen. An improved construction of the paper apron is also provided in which 45 there is ample room for the insertion of any number of sheets upon which it is practicable to write.

Referring now more particularly to the drawings, a pair of end plates 10 are connected by rods 11 and pivotally mounted in the end plates is a platen 12. Also pivoted in the end plates 10 is a rock shaft 13 preferably formed with one flattened side.

Secured to the lowermost rod 11 is a 55 bracket 14 for raising and lowering the

platen, and extending upwardly from the bracket is an extension 15 forming a support for the middle of the rock shaft 13 and in which the rock shaft is freely rotatable.

A paper apron 16 is formed to extend beneath the platen with the rear side somewhat above the front side of the apron and curved slightly away from the platen. This apron is formed with depending ears 17, 18 and 19 adjacent each end thereof, in each of which is a perforation, the perforation of ears 17 being circular in form to form a close fitting connection for a rear roller shaft 20, and the other ears 18 and 19 are preferably formed with slotted perforations, the slots 70 of the perforations 19 being preferably curved on a radius of which the axis of the rear roller shaft 20 is the center.

Disposed beneath the paper apron 16 are frame elements 21 connected by a shaft 22 75 to which they are both affixed. Disposed on the rear roller shaft 20 are rollers 23, preferably four in number, and spaced apart on the shaft. These rollers 23 are preferably located in openings at the rear of the paper 80 apron made by forming with tongues 24. Attached to one or more of the tongues 24 is one end of a spring 25, the other end of which is connected to a fixed pin or projection 26 which may be connected to the 85 extension of the bracket 14. One arm of each of the frame members 21 is journaled on the rear roller shaft at a point between two of the rollers so that it does not bear on the end of the shaft. Another arm of each 90 of the frame members is journaled correspondingly to a front roller shaft 27 the ends of which extend loosely through the perforated ears 19. Mounted upon this shaft are front rollers 28 which press against 95 the platen through apertures 29 in the apron 16. The front side of the paper apron is held in close relationship with the paper on the platen by the spring 25, and also by means of springs 30 which are coiled around 100 the shaft 27 with one end in engagement with the front of the paper apron and the other end in engagement with a scale 31.

This scale 31 is also secured to the forward arms of the frame members 21 and the lower edge of the scale is stiffened by a corrugation 32, the scale being held in position against the platen by means of the springs 30 adjacent the frame elements 21. To reduce the spring pressure on the front of the 110

paper apron, the end of the spring which contacts with the apron may be connected with the frame members 21.

Extending from each of the frame members 21 is a bracket 34 provided with a projection 35, and mounted on the shaft 11 are abutments 36 each adapted to receive one end of a spring 37, the other end of which is held in place by the projection 35 of one 19 of the brackets. The tendency of these springs 37 is to press the frame members and consequently the rollers supported thereby firmly against the platen 12. The springs 30 on the front roller shaft tend to press 15 the front of the paper apron against the platen, and the spring 25 connected to the rear end of the paper apron tends to rotate the front of the paper apron against the platen about the ears 17 as an axis. 20 Pivoted to one of the end plates 10 is a lever 38 which has a finger gripping portion 39 at the upper end, and a slot 40 in which a pin 41 secured to the end plate engages to limit the movement of the lever. Connected to the rock shaft 13 is an arm 42 and joining this arm and the lever 38 is a link 43 which is pivoted to the lever at a point movable on either side of a line connecting the pivot point of the lever and the pivot 25 point of the link by which it is connected to the arm 42, so that when the pivot point of the link 43 at which it is connected to the lever 38 is moved on either side of the said center line the lever will be locked in 30 position. Also secured to the rock shaft 13 are arms 44 the outer end of each being loosely connected by means of a fastening device 45 with a perforated ear 18 of the paper apron. Intermediate the arms 44 are 35 short arms 46 to prevent endwise shifting of frame members 21 and each of the arms 44 and 46 is provided with a shoulder 47 which is adapted to engage the paper apron when the shaft 13 is rotated, as shown by Fig. 7, 40 and just before the lever 38 reaches the position shown by this figure so that the front side of the paper apron is lifted clear of the platen, as shown by this figure.

In its normal position the paper apron and 50 the front and rear rollers are pressed toward the platen by means of springs 37 which engage the frame members upon which the roller shafts are carried and the front side of the paper apron is pressed toward the 55 platen by springs 25 and 30. The scale 31 being also spring-pressed tends to hold the paper close to the platen adjacent the printing point so that the paper may be written on close to the very bottom, when desired. 60 When the operating lever 38 is moved forward to the position shown by Fig. 7 the first action is to take up the lost motion by moving the fastening devices 45 to the bottom of the perforations of the ears 18. A 65 continued movement of the lever moves the

rollers away from the platen adjacent the pressure of the springs 37, and the front arms of the frame members 21 being connected to the paper apron by the loose connection of the shaft 27 with the ears 19 cause the rear roller to be withdrawn first from contact with the platen whereupon the spring 25 presses the front side of the paper apron against the platen until the paper apron is withdrawn to such an extent that it is engaged by the shoulders 47 of the arms 44 and 46, whereupon the movement of the rear rollers away from the platen is stopped and the front rollers are moved to a greater extent until the paper apron assumes the position as shown by Fig. 7. This construction provides for firmly adjusting the paper apron to accommodate various thicknesses of writing material which is necessary when using one or more thicknesses of paper, 85 cards or the like, or in doing manifold work. This arrangement provides a rigid form of construction; for the front end of the paper apron is independent of the front rollers to the extent of the loose connection between them and the apron and the apron is automatically adjustable to whatever thickness of material is being used in the machine while the lever 38 reaches above the paper apron at its front side so as to assist in writing nearer to the bottom of a sheet of paper.

What I claim is:

1. A typewriter platen, a paper apron having sets of perforated depending ears about one side of which the apron is movable, the other sets being formed with slots to permit the rotation of the apron about the axis of the first named set to a limited extent, and means to press the apron toward the platen.

2. A typewriter paper feeding mechanism comprising a loosely mounted spring pressed paper apron with depending perforated ears, means for moving the apron bodily, an oscillatable frame connected with the apron upon which one side of the apron is pivotally connected, and a lost motion connection between the frame and the apron at the other side of the latter whereby an oscillation of the apron with respect to the frame is possible.

3. Typewriter paper feed mechanism comprising a platen, a paper apron movable toward and from the platen having sets of depending perforated ears one set of which is slotted and curved upon a radius extending from the axis of another set of ears, a movable frame pivotally connected to the last named set of ears, and a lost motion connection between the frame and the slotted ears whereby an oscillating movement of the apron is permitted with respect to the frame.

4. Typewriter paper feed mechanism comprising a platen, a paper apron movable to-

ward and from the platen with sets of perforated ears extending therefrom, one set of which is slotted, a friction roller shaft pivotally mounted in one set of ears, another 5 friction roller loosely mounted in the slotted ears, and rigid means forming a fixed bearing for both of said shafts.

5. Typewriter paper feed mechanism comprising a platen, a paper apron movable toward and from the platen with sets of perforated ears extending therefrom, one set of which is slotted, a friction roller shaft pivotally mounted in one set of ears, another 10 friction roller loosely mounted in the slotted ears, rigid means forming a fixed bearing 15 for both of said shafts, and resilient means for tending to press the rigid means and the roller shafts in the direction of the platen.

6. Typewriter paper feed mechanism comprising a platen, a rear feed roller shaft, a 20 front feed roller shaft, means to rigidly connect the two shafts, and a paper apron movable toward and from the platen with sets of perforated ears in one set of which the 25 rear roller shaft is pivoted and having slots in the other set of ears through which the front roller shaft extends loosely whereby the front of the paper apron may oscillate to a limited extent about the axis of the rear 30 roller shaft.

7. Typewriter paper feed mechanism comprising a platen, a rear feed roller shaft, a front feed roller shaft, means to rigidly connect the two shafts, a paper apron movable toward and from the platen with sets of perforated ears in one set of which the 35 rear roller shaft is pivoted and having slots in the other set of ears through which the front roller shaft extends loosely whereby the front of the paper apron may oscillate to a limited extent about the axis of the rear 40 roller shaft, and means tending to press the paper apron away from the shaft at the front side in the direction of the platen.

45 8. Typewriter paper feed mechanism comprising a platen, a frame in which the platen is mounted, a paper apron having sets of perforated ears one set of which is slotted, a rear feed roller shaft mounted in one set of 50 ears, a front feed roller shaft loosely mounted in the slotted ears, a rigid frame connecting the shafts, the front of the apron being oscillatable with respect to the rigid frame, means for withdrawing the apron 55 from the platen, and a spring connected to the rear of the apron and to the frame for supporting the platen for pressing the front of the apron in the direction of the platen when the apron is withdrawn from the 60 platen.

9. Typewriter paper feed mechanism comprising a platen, a frame in which the platen is mounted, a paper apron having sets of perforated ears one set of which is slotted, a 65 rear feed roller shaft mounted in one set of

ears, a front feed roller shaft loosely mounted in the slotted ears, a rigid frame connecting the shafts, the front of the apron being oscillatable with respect to the rigid frame, means for withdrawing the apron 70 from the platen, a resilient means tending to press the frame connecting the shafts in the direction of the platen, a spring connected to the rear of the apron and to the frame for supporting the platen for pressing the 75 front of the apron in the direction of the platen when the apron is withdrawn from the platen, and additional resilient means tending to press the front of the paper apron away from the front roller shaft against the 80 platen.

10. Paper feed mechanism comprising a platen, a paper apron movable toward and from the platen having sets of perforated ears and spaced apertures, roller shafts 85 loosely mounted in the ears, feed rollers mounted on the shafts and adapted to contact with the platen through the apertures, and a rigid frame connecting the shafts at points between the rollers and spaced from 90 the ends of the shafts.

11. The combination with paper feed mechanism, of a platen, a paper apron movable toward and from the platen and independently oscillatable about a rear longitudinal axis, resilient means tending to press the front of the paper apron in the direction of the platen, and means to bodily withdraw the apron from the platen, the 95 said resilient means causing the front to be 100 yieldingly withdrawn before the rear is withdrawn.

12. The combination with paper feed mechanism, of a platen, a paper apron movable toward and from the platen and independently oscillatable about a rear longitudinal axis, resilient means tending to press the front of the paper apron in the direction of the platen, means to withdraw the apron 105 from the platen, and a stop for engaging 110 the rear of the apron after a predetermined extent of movement thereof whereby the front of the apron will be withdrawn.

13. The combination with paper feed mechanism, of a platen, a paper apron movable toward and from the platen and independently oscillatable about a rear longitudinal axis, resilient means tending to press the front of the paper apron in the direction of the platen, means to withdraw 115 the apron from the platen comprising a rock shaft connected to the apron, and a plurality of arms mounted on the rock shaft for engaging the apron after a predetermined movement thereof whereby first the rear and 120 then the front of the apron is withdrawn.

14. Paper feed mechanism comprising a platen, a paper apron movable toward and from the platen with sets of depending lugs some of which are slotted, resilient means 125

- tending to press the front of the apron in the direction of the platen, feed roller shafts one of which is fixedly pivoted in the rear of the apron and another of which is loosely mounted in the front set of ears, a spring-pressed frame connected to the shafts tending to press them in the direction of the platen, and means for withdrawing the apron from the platen comprising a lost motion connection with one set of lugs whereby the apron may be independently oscillatable about the rear roller shaft as an axis when the apron as a whole is withdrawn from the platen.
15. Paper feed mechanism comprising a platen, a spring-pressed apron movable to and from the platen and also independently oscillatable upon an axis at the rear of the apron, and an independently spring-pressed scale mounted at the front of the apron adapted to engage the platen in front of the front edge of the paper apron.
16. Paper feed mechanism comprising a platen, a support movable toward and from the platen, and an independently spring-pressed scale mounted on the support and adapted to engage the platen at a point close to the printing line to engage the bottom of material to be printed for writing close to the bottom edge of the material.
17. In paper feed mechanism, the combination with a platen, of feed roller shafts, a spring-pressed frame for the shafts, and an independently spring-pressed scale mounted on the shafts and adapted to be pressed against the platen just below the printing line.
18. Paper feed mechanism comprising a platen, a paper apron movable toward and from the platen and independently oscillatable about a longitudinal axis at the rear of the apron, means tending to press the front of the apron in the direction of the platen, feed roller shafts, a spring-pressed frame for the shafts pivotally connected to the paper apron at the rear thereof and independently oscillatable with respect thereto at the front of the apron, means

to withdraw the apron and the frame from the platen, and an independently spring-pressed scale pivotally connected to the front roller shaft and movable to engage the platen on a line nearer the printing point than the front edge of the paper apron.

19. Typewriter paper feed mechanism comprising a platen, front and rear roller shafts, rollers mounted on the shafts, frame members forming journals for the shafts, a bar rigidly connected to the frame members forming a rigid frame structure in the form of an H, and means for positively moving the said structure toward and from the platen.

20. Typewriter paper feed mechanism comprising a platen, a pair of shafts, rollers mounted on the shafts, frame elements connecting the shafts at spaced distances, a bar rigidly connecting the frame elements and forming a solid structure, brackets extending from the frame member, a bar disposed below the frame members having abutments extending therefrom, and springs disposed between the abutments and the brackets tending to press the frame members in the direction of the platen.

21. Typewriter paper feed mechanism comprising a rotatable platen, roller shafts, rollers mounted on the shafts, frame members connecting the shafts, a bar rigidly connecting the frame members forming a solid frame, means tending to press the solid frame in the direction of the platen, operating means for overcoming the tension of the spring comprising a rock shaft, and arms mounted on the rock shaft adjacent the frame members to prevent the endwise movement of the solid frame.

In testimony whereof I have signed my name to this specification, in the presence of two subscribing witnesses, on this 17th day of October A. D. 1914.

ALVAH C. ROEBUCK.
